Specification for Design.

Patented Oct. 7, 1919.

Application filed May 13, 1919. Serial No. 296,936. Term of patent 14 years.

To all whom it may concern:

Be it known that I, EDWIN BROWN, a citizen of the United States, residing at No. 1921 Andrews avenue, borough of Bronx, city of New York, in the county of Bronx, State of New York, have invented a new, original, and ornamental Design for a Combination Set of Cooking Utensils, of which the following is a specification, reference being had to the accompanying drawing, forming part thereof, wherein—

Figure 1 is a view in side elevation of a combination set of cooking utensils, showing my new design.

Fig. 2 is a plan view of the same.

I claim:

The original design for a combination set of cooking utensils, as shown.

EDWIN BROWN.
